UNITED STATES PATENT OFFICE.

SAMUEL JAMES AND JEREMIAH K. SANDERS, OF LEBANON, MISSOURI.

SPINDLE-DRIVING DEVICE FOR SPINNING-MACHINES.

SPECIFICATION forming part of Letters Patent No. 446,751, dated February 17, 1891.

Application filed August 20, 1889. Serial No. 321,340. (No model.)

To all whom it may concern:

Be it known that we, SAMUEL JAMES and JEREMIAH K. SANDERS, of Lebanon, in the county of Laclede and State of Missouri, have 5 invented a new and useful Improvement in Spindle-Driving Devices for Spinning-Machines, of which the following is a full, clear, and exact description.

Our invention relates to an improvement in 10 banding and tension devices for spinning and twisting machines.

The object of our invention is to provide a simple and economical construction and arrangement of parts for the banding and tension mechanism of a spinning-jack and yarn-twisting-machine, whereby the series of spindles in a section of the machine will be simultaneously rotated in the same direction by a single band, the tension of said band being 15 automatically regulated in an efficient manner with a new and improved tension mechanism.

A further object is to provide the novel 20 tension device hereinafter mentioned with a self-feeding oiler, which will enable the apparatus to be run longer without stoppage than can otherwise be effected.

With these objects in view, our invention 25 consists in the novel construction and combination of the several parts, as will be hereinafter fully set forth, and pointed out in the claims.

Reference is to be had to the accompanying 30 drawings, forming a part of this specification, in which similar letters of reference indicate corresponding parts in all the figures.

Figure 1 is an end elevation in section of 35 the device. Fig. 2 is a front elevation of the spindles and their supports. Fig. 3 is a top plan view of a section of a spinning-jack, the spindles being shown in section, and Fig. 4 is an enlarged detached sectional view of 40 one of the important features of our invention.

45 A is the frame of a spinning-jack, of which A' and A² are parallel front rails, which support the series of spindles B B' B², which are spaced apart and seated in suitable boxes f, which receive their lower ends and permit 50 the spindles to rotate therein. On the upper

rail A² supporting-boxes g are fixed to receive and support revolvably the bodies of the spindles.

At a proper point rearward of the gang of spindles a cylindrical band-roller C is supported by its journal ends e on the frame of the jack, which roller extends throughout the length of the spinning-machine, and is revolved by any suitable means. (Not shown.)

55 It is preferred to arrange a convenient number of the spindles in a section. While the number may be varied, it is found advantageous in a jack having an aggregate number of spindles equal to two hundred and forty to run twenty-four spindles together. The 60 end spindles B' B² have the whirls c c' and c² c², which whirls are each formed with two belt-grooves, as shown.

The intermediate spindles B of a section 65 are furnished with whirls c⁴, which are singly 70 grooved to receive a belt.

A belt-tightener or tension device is furnished to regulate the draft of the belt G. Said tension-regulator consists of a guideway D, which is made extensible by its support on a slotted bracket D³, to which it is bolted at b, the opposite end of the guideway being furnished with a flange D', that is bolted or otherwise attached to the jack-frame A.

75 The guideway D is preferably constructed as a flat metal bar having a longitudinal slot formed in it to receive the sliding block E, which is loosely fitted therein in a manner to prevent displacement and allow it to reciprocate freely throughout the extent of the elongated slot it lies in.

80 On the sliding block E a grooved whirl F is supported to rotate by mounting it loosely on a stud-bolt a², which is firmly inserted in the sliding block and secured in place by a nut a³. (See Fig. 4.) Upon the upper end of the stud-bolt a² an oil-cup a' is formed. It, constituting the head of the bolt, retains the whirl F from displacement. The oil-chamber 85 of the cup a' is formed as shown, and axially central with the body of the bolt a² a feed-hole h penetrates the bolt a short distance and then intersects a transverse hole i, which is in proper position to convey oil to lubricate 90 95 100

the whirl F. Wool or cotton in small quantity is inserted in the feed-channels mentioned, which restrains the flow of oil and graduates its delivery to continually supply the lubricant as it is needed.

5 The bracket D², which supports the front end of the guideway D, has its slotted projecting portion inclined from a horizontal plane downwardly, thus affording a proper 10 support for the guideway, which is downwardly inclined from front to rear end, as shown in Fig. 1.

15 A coiled spring I is attached to the front portion of the jack-frame, or to the bracket D², as shown, by one of its ends, said spring extending rearwardly below the guideway D in line with it.

20 The rear end of the spring I is connected to a cord or other flexible strand J, which is passed around the grooved pulley J', that is pivoted on the lower end of the guideway-bar in its slot, and said cord being returned above the guideway is attached by its other end to the sliding block E at d. The connection of 25 the spring I to the sliding block E by the cord J, as stated, will draw the block toward the lower end of the guideway.

25 An endless belt G is provided to drive all 30 the spindles of a section at one time in the same direction. To effect this operation the belt is given a half-turn over the grooved whirl F, which is mounted on the sliding block E, as shown in Fig. 3. It is then extended diagonally toward the end spindle B', and around the lower whirl c' of said spindle, 35 thence rearwardly over the cylindrical roller C and returned, as at 2, to the upper whirl c of the spindle B'. From the whirl c' the belt G is extended rearward and upward, passing 40 around the cylinder C and bearing on its rear half, thence diagonally sidewise, so as to engage the whirl c' on the first spindle B, nearest the end spindle B'. From the whirl of the said spindle B the belt is drawn straight 45 back, as at 4, and passes around the cylinder C, then forward diagonally, as at 5, around the whirl of the second spindle from the end spindle B', then straight to the rear and upwardly, to again pass around the rear half of 50 the cylinder, as shown at 6, Fig. 3. The belt is arranged to successively engage the series of whirls of the several intermediate spindles B in manner similar to that already explained, and at the end spindle B', which terminates 55 the section of the spinning-jack driven by one endless belt, the belt G, which has been diagonally extended from the lower side of the cylinder C to engage the upper whirl c', as at 7, is thence rearwardly and upwardly 60 drawn, as at 8, to pass over and around the cylinder, thence forward and around the groove in the whirl c' on the spindle B'; and thence diagonally to an engagement with the whirl F on the sliding carriage E before 65 mentioned.

It will be evident from the description

given that the endless belt G will transmit rotary motion from the cylinder C to all of the spindles B B' B² of a section, which may be any convenient number of spindles.

70 In arranging the belt G it is so proportioned in length relatively that the sliding block E will be drawn up near the top of the guideway D, so that the full contractile force of the spring I will be available to take up 75 slack which may occur in the belt from use.

A number of manifest advantages result 80 from the novel construction and arrangement of parts herein described. The more essential are that the number of belts used to transmit motion to the spindles is reduced; the tension device is automatically and economically oiled; the tension arrangement will be effective for a long time, avoiding the frequent cutting of the belt to take up slack; 85 and further, the motion of the spindles in a section being transmitted thereto by a single belt is more regular than in ordinary spinning-jacks using a number of independent belts for the purpose. The tension-guideway 90 D being extensible, its length may be adjusted to suit jack-frames of different dimensions considered from front to rear of same, which is of advantage where frames of varied width are fitted up to use our improved 95 tension and banding device.

Having thus fully described our invention, we claim as new and desire to secure by Letters Patent—

1. In a spinning-machine, the combination, 100 with a frame, a cylindrical roller, a series of spindles comprising a section, and loosely secured on the frame, a whirl having two grooves mounted on each end spindle of the section, and a single-grooved whirl attached 105 to each intermediate spindle of the section, of an endless belt which engages with a half-turn the double and single grooves of the whirls on the end and intermediate spindles and alternately with the cylindrical roller, 110 substantially as set forth.

2. In a spinning-machine, the combination, 115 with a frame, a sliding tension device, a cylindrical roller, a series of revoluble spindles comprising a section and mounted on the frame, a double-grooved whirl for each end spindle of the section, and a single-grooved whirl for each intermediate spindle in the section, of an endless belt alternately engaged 120 with the cylindrical roller and the whirls of the spindles and also with the sliding tension device, substantially as set forth.

3. In a banding and tension device for spinning-machines, the combination, with a frame, a cylindrical roller, a series of spindles, 125 each having an attached grooved whirl, and an endless belt, of an automatic tension-regulating device comprising an extensible guideway, a sliding block adapted to travel on the guideway, a loose whirl mounted on a 130 fixed stud-bolt attached to the sliding block, an automatic oiler for the loose whirl, a spiral

spring which is attached to the frame and also to the sliding block by a flexible connection, and a pulley over which said connection passes, substantially as set forth.

5 4. In a band-tensioning device for spinning-machines, the combination of a slotted bar, a block arranged upon said bar and having a portion that works in the slot, a bolt passing through said block and bar, a spring

connected with said block, and an idler-pulley mounted on the spindle of the bolt, substantially as specified.

SAMUEL JAMES.
